CONDENSER FOR MECHANICAL
REFRIGERATORS

Walter R. Ramsaur, Racine, Wis., assignor to
General Motors Corporation, Detroit, Mich., a
corporation of Delaware

Application January 13, 1939, Serial No. 250,774

4 Claims. (Cl. 257—139)

This invention relates to the art of mechanical refrigeration and more particularly to an improved tube and heat transfer construction for the condensation of refrigerant.

An object of the invention is to provide a simple and low cost structure in which the parts mutually reinforce each other and insure rapid exchange of heat.

In the drawing Figures 1 and 2 are elevations showing optional forms of tube assemblies, some of the radiating fins being omitted for clarity, and Figure 3 is a detail perspective view of the interfitting heat exchange parts.

The condenser assembly consists essentially of a long continuous tube which for compactness may be bent upon itself either back and forth as illustrated in Figure 1 or spirally as in Figure 2. In either case a corrugated separator is interposed between the recurring lengths of tubing.

The tube comprises a pair of complementary narrow strips 1—1 arranged face to face, each with a pair of flat and relatively wide side wings 2—2 bonded to the corresponding wings of its neighboring strip together with a relatively narrow rib or semi-circular embossment 3 running medially of the strip and throughout its entire length for cooperation with the aligned rib in the mating strip to form the enclosed tube space. The separator or spacer strip 4 is of zigzag formation with its apices bearing against adjacent wings and having a central depression or seating formation 5 to bridge or receive therein the tube embossment 3. The resulting nested relation interlocks the parts together against displacement and insures their mutual reinforcement.

In manufacture a ribbon of selected width is passed through a roll die machine to form the spacer strip 4 and another ribbon is passed through a suitable die to press the embossment 3 in the strip 1. The formed strips are cut to desired length and two of the strips 1 are brought together face to face with the ribs 3 projecting away from one another. They are then bent either to the zigzag or spiral shapes of Figures 1 and 2, respectively, with the separator 4 interposed in proper position. In the case of Figure 1 an additional supporting and spacing frame 6 may be placed over the top and bottom of the assembly. The whole assembly is then dipped in solder for the capillary flow of the hot metal between the contacting surfaces for joining and sealing the parts. Pipe sections 7 inserted and sealed in the opposite ends of the condenser tube will serve to connect the assembly in the system circuit.

The resulting assembly possesses inherent strength and good heat dissipation characteristics. It will be noted that a considerable amount of fin surface is present in relation to the size of the tube space and further that the side wings 2—2 constitute heat radiating fins integral with the tube and these are augmented by the large radiating surface afforded by the corrugated spacer 4 whose fins extend transversely of the plane of the wings 2. The exchange of heat is 10 between the fluid flowing through the tube space and that flowing through the assembly or between the tubes and over the fin surface.

I claim:

1. In a heat exchanger, a pair of complementary strips having aligned and relatively narrow embossments affording tube space and relatively wide side wings joined together to seal the space and afford axially extending heat radiating fins integral with the tube, and auxiliary heat radiating fins extending transversely of the plane of the first mentioned fins and including a corrugated strip having its apices secured in thermal contact to the wings on both sides of the narrow embossment with seating formations in interlocking relation to an adjacent tube embossment. 15

2. In a heat exchanger, a tube comprising a pair of complementary sheet metal ribbons each having medially thereof a tube forming rib and a pair of oppositely disposed axially extending heat radiating fins joined throughout their surface area to the corresponding fins of its complementary ribbon, and a series of transversely projecting supplementary heat radiating fins bonded to the first mentioned fins. 20

3. In a heat exchanger, a corrugated separator strip having tube seats in the crests thereof, and a tube fitting said seats and having a pair of oppositely disposed axially extending heat radiating fins bonded to said crests on both sides of 25 the tube seats. 30

4. In a heat exchanger, a pair of tube spacer strips of corrugated formation having tube seats in the crests thereof, a tube between said spacer strips comprising a pair of complementary ribbons having aligned tube forming ribs medially thereon fitted to said seats and each ribbon having a pair of oppositely disposed axially extending heat radiating fins joined on the inner faces to the mating fins of the complementary 40 ribbon and joined in heat transfer abutment on their outer faces to the crests of the adjacent spacer strip on both sides of the tube seats. 45
